UNITED STATES PATENT OFFICE.

MANNING L. NIX, OF PARIS, TEXAS.

COTTON-GIN FEEDER.

SPECIFICATION forming part of Letters Patent No. 274,961, dated April 3, 1883.

Application filed June 17, 1882. (No model.)

To all whom it may concern:

Be it known that I, M. L. NIX, a citizen of the United States, and a resident of Paris, in the county of Lamar and State of Texas, have 5 invented a new and valuable Improvement in Cotton-Gin Feeders; and I do hereby declare that the following is a full, clear, and exact description of the construction and operation of the same, reference being had to the annexed drawings, making a part of this specification, and to the letters and figures of reference marked thereon.

Figure 1 of the drawings is a plan view of my device. Fig. 2 is a vertical sectional view 15 of the same, and Fig. 3 is a transverse sectional view.

This invention has relation to cotton-gin feeders; and it consists in the construction and novel arrangement of parts, as will be 20 hereinafter fully described, and particularly pointed out in the claims appended.

My object is to provide for the cotton-gin in general use a cheap and effective feeder, automatic in its action and adapted to gins of varying sizes.

Referring by letter to the accompanying drawings, *a* designates the frame or casing of the gin-feeder, which rests on and above the gin, and is operated by a belt running from a 30 pulley on the saw-shaft of the cotton-gin to a pulley on the end of the drum-shaft in the feeder. The casing *a* forms the hopper, into which the cotton is placed or thrown, and its bottom is made of alternating sections *b* and *c*, the sections *b* being connected to front and rear cross-bars, *d* and *d'*, directly, and the sections *c* being located between the slats *e* of these sections, as shown. A rod, *f*, traverses the casing *a* near its lower edge, and to this rod *f* 35 are connected, near their rear ends, by loop-rods *g* and staples *g'*, the slats of the alternating sections of the hopper-bottom, *b* and *c*. These alternating sections *b* and *c* have their respective slats provided near their front ends with depending bended or hooked arms *h*, the hooks *h'* of which engage alternating cranks *i* and *i'* of a crank-shaft, *k*, which, when operated, gives them an alternating rising and falling motion. While one set of slats is feeding on- 40 ward the cotton the other set is being drawn back beneath the mass of cotton to in turn

feed it onward. To prevent the seed-cotton from too rapidly approaching the throat of the feeder, I provide an adjustable comb, *l*, mounted upon bearings at the sides of the casing *a*. This comb *l* consists of a toothed frame, *m*, upon a crank-shaft, *n*, having bearings in the arms *o*, and it is connected by a hinge-connection, *p*, through an arm, *q*, to a cross-bar, *r*, near the rear of the casing *a*, as shown. The comb *l* is rendered adjustable on its shaft by means of the elongated slots *n'* in the ends of its frame, one of these slots being shown in dotted lines in Fig. 2, set-screws *n''*, above and below the shaft *n*, being employed to hold 55 the comb to its adjustment. The object of the adjustment is to permit the comb to be raised or lowered to suit either fast-feeding or slow-feeding cotton-gins.

t designates the ordinary screen through 70 which the dust passes.

t designates the ordinary drum, having a miter-gear, *u*, upon one end of its shaft, and a pulley, *u'*, upon the other end, to receive the band from the saw-shaft of the cotton-gin.

The oscillatory or vibratory comb *l* may be 75 connected with the drum of the feeder by a belt running from a pulley on the drum-shaft to a pulley, *o'*, on the shaft *n*. A shaft, *v*, has its bearings in brackets at one side of the casing *a*, and is provided with a miter-gear, *w*, meshing with the miter-gear *u* on the drum-shaft. A screw-gear, *x*, at its front end engages the teeth of a cog-wheel, *x'*, on the crank-shaft *k*. A ratchet-wheel, *k'*, is interposed between the cog-wheel *x'* and the side 80 of the casing *a*, and is secured to the crank-shaft *k* by a set-screw in the ordinary manner. A detent, *z*, is pivoted to the side of the case 85 *a*, and engages the ratchet-wheel *k'* and prevents a backward movement of the crank-shaft *k*.

The feeder sometimes fails to feed the cotton 90 onwardly as rapidly as may be desired; and to enable the attendant to remedy this defect, when it occurs, the shaft *k* is provided with a crank-handle, *y*, as shown, which may be grasped by the operator to accelerate the feed.

I am aware that an adjustable oscillating rake or comb is not new in cotton-gin feeders, 95 and I do not broadly claim this feature herein.

Having fully described my invention, what I

claim, and desire to secure by Letters Patent, is—

1. In a cotton-gin feeder, the combination, with the driving mechanism, of the alternating sections *b* and *c*, the shaft or rod *f*, loop-rods *g* and staples *g'*, the crank-shaft *k*, and hooked rods *h h'*, substantially as specified.

2. In a cotton-gin feeder, the combination, with the alternating sections of the feeder-bottom and mechanism for operating the same, of the

adjustable comb *l*, the crank-shaft *n*, hinge-connection *p*, arm *q*, and cross-bar *r*, substantially as specified.

In testimony that I claim the above I have hereunto subscribed my name in the presence of two witnesses.

MANNING LAFAYETTE NIX.
